[57] **CLAIM**

The ornamental design for a handle assembly for an upright
deep cleaner, as shown and described.

DESCRIPTION

FIG. 1 is a perspective view of a first embodiment of a handle assembly for an upright deep cleaner according to the invention with the base module shown in phantom;
FIG. 2 is a front elevational view for the first embodiment;
FIG. 3 is a rear elevational view of the first embodiment;
FIG. 4 is a right side elevational view of the of the first embodiment;
FIG. 5 is a left side of the first embodiment;
FIG. 6 is a bottom plan view of the first embodiment;
FIG. 7 is a top plan view of the first embodiment;
FIG. 8 is a perspective view of the design for a second embodiment of a handle assembly for an upright deep cleaner according to the invention with the base module and wheels shown in phantom;
FIG. 9 is a front elevational view of the second embodiment;
FIG. 10 is a rear elevational view of the second embodiment;
FIG. 11 is a right side elevational view of the second embodiment;
FIG. 12 is a left side elevational view of the second embodiment;
FIG. 13 is a bottom plan view of the second embodiment;
FIG. 14 is a top plan view of the second embodiment;
FIG. 15 is a perspective view of the design for a third embodiment of a handle assembly for an upright deep cleaner according to the invention with the base module, wheels, and hose/cord wrap assembly shown in phantom;
FIG. 16 is a front elevational view of the third embodiment;
FIG. 17 is a rear elevational view of the third embodiment;
FIG. 18 is a right side elevational view of the third embodiment;
FIG. 19 is a left side elevational view of the third embodiment;
FIG. 20 is a bottom plan view of the third embodiment; and,
FIG. 21 is a top plan view of the third embodiment.
FIGS. 15-21 are shown separate for clarity of illustration,
the claim being directed to the multiple embodiments shown
in FIGS. 1-14. The details shown in broken lines in FIGS.
1-5 and 7-21 are shown for illustrative purposes only and
form no part of the claimed design.
